UNITED STATES PATENT OFFICE.

FAY McFADDEN, OF RUTLAND, VERMONT, ASSIGNOR TO BAY STATE OPTICAL COMPANY, OF ATTLEBORO, MASSACHUSETTS, A CORPORATION OF MAINE.

DESIGN FOR AN EYEGLASS FRAME.

Application filed October 24, 1927. Serial No. 23,855. Term of patent 14 years.

To all whom it may concern:

Be it known that I, FAY McFADDEN, a citizen of the United States, residing at Rutland, in the county of Rutland, State of Vermont, have invented a new, original, and ornamental Design for Eyeglass Frames, of which the following is a specification, reference being had to the accompanying drawing, forming part thereof.

In the drawing Figure 1 is a front elevation and Figure 2 is a top plan view of an eyeglass frame showing my new design.

I claim:

The ornamental design for an eyeglass frame as shown.

FAY McFADDEN.
